UNITED STATES PATENT OFFICE.

LUDVIG KORÁB, OF RENVILLE, MINNESOTA.

APPARATUS FOR MANUFACTURING FLOUR.

SPECIFICATION forming part of Letters Patent No. 726,172, dated April 21, 1903.

Application filed April 21, 1902. Serial No. 103,997. (No model.)

To all whom it may concern:

Be it known that I, LUDVIG KORÁB, a subject of the Emperor of Austria-Hungary, residing at Renville, in the county of Renville and State of Minnesota, have invented a new and useful Apparatus for Manufacturing Flour, of which the following is a specification.

This invention relates to an apparatus for the manufacture of flour, and has for its object the production of an apparatus wherein the products of a number of independent reduction-mills are received and separately and independently treated and all the apparatus operated from one source of power.

Another object of the invention is the production of an apparatus wherein the fine flour is separated from the coarse material and refuse in one portion of the apparatus by gravity and the valuable particles of this coarser material separated from the refuse in a separate and independent apparatus by the combined action of gravity and induced air-currents.

Further objects of the invention will appear in the description following and be specifically pointed out in the claims.

The apparatus herein shown comprises a series of superimposed sieve-boxes arranged in pairs, the lower box of each pair mounted upon ball-bearings disposed to operate longitudinally of the casing and the upper sieve-box of each pair supported upon its companion lower box by ball-bearings disposed to operate transversely of the lower box and with means for imparting a gyratory motion independently to the upper boxes and a longitudinal vibratory movement to the lower sieve-boxes. Each box will be divided into separate independent compartments each containing an independent system of separating screens and chutes and each adapted to receive the product of separate independent reduction-mills. The upper boxes are designed to separate the fine flour from the coarser material by gravity only, while the lower boxes are designed to receive this coarser material from the upper boxes and separate the valuable particles from the refuse by the combined action of gravity and induced air-currents.

All of the various steps required to separate the fine flour, the different grades of fa-

rina and middlings, the bran, and other valuable particles, as well as the refuse, are accomplished in this one machine and from one single source of power, which machine by its peculiar construction and arrangement of parts is so extremely simple and compact that a mill of very large capacity can be erected in a comparatively small area and operated by a comparatively small power.

The arrangement of the mechanism is clearly shown in the drawings, in which—

Figure 1 is a side elevation of the apparatus, showing the lower sieve-boxes in vertical section. Fig. 2 is a front elevation thereof with the top sieve-boxes shown in vertical section. Fig. 3 is a horizontal section, on the line X X of Fig. 2, of one of the upper boxes. Fig. 4 is a bottom plan view of one of the upper boxes. Fig. 5 is an enlarged sectional detail of one of the screen-cleaning brushes employed on the screens of the upper boxes. Fig. 6 is a horizontal section of one of the lower boxes on the line y y of Fig. 1. Fig. 7 is a bottom plan view of one of the lower boxes. Fig. 8 is an enlarged sectional detail of one of the brushes employed on the screens of the lower boxes. Fig. 9 is a sectional detail illustrating a modification in the construction. Fig. 10 is a bottom plan view of the upper box shown in the modified form in Fig. 9.

Each pair of sieve-boxes being exactly alike, like characters are employed to designate corresponding parts in each. The upper boxes are designated by 10 and the lower boxes by 11. Two pairs of the boxes are shown and each box divided into four compartments by transverse partitions 12 and 13 and longitudinal partitions 12^a and 13^a; but a greater or lesser number of pairs of sieve-boxes may be employed and each box may be divided into a greater or lesser number of the compartments, according to the capacity of the mill required. Each compartment in each upper box will have its corresponding or companion compartment in its corresponding or companion lower box. The boxes will be arranged, preferably, one above the other, as shown, and surrounded by an inclosing framework 14 of any approved construction. Each lower box 11 will be supported upon ball-bearings formed by balls 15, operating between grooved

ribs or troughs 16 and 17, one set on the box 11 and one set on the framework 14, and disposed longitudinally of the box at four points, as shown in Figs. 1 and 2. Each upper box 5 is supported upon its companion lower box by ball-bearings formed by balls 18, operating between grooved ribs or troughs 19 20, one set on the lower box 11 and the other set on the upper box and disposed transversely 10 of the lower box or at right angles to the grooved ribs or troughs of the lower box and at four points thereon, as shown in Figs. 2 and 4. Supported vertically in the framework 14 and operating through a central cavity in the lower box 11 of the upper pair is a shaft 21, having cranks 22 23 on its ends engaging each upper box, so that the revolution of the shaft will impart a gyratory motion to the upper boxes. The upper boxes 20 being connected to the lower boxes only by the ball-bearings interposed between them, and the bearing-troughs between the boxes being at right angles to the bearing-troughs beneath the lower boxes, and the cranks 22 25 23 imparting both a lateral and longitudinal strain upon the upper boxes, these lateral strains will cause the lower boxes to move upon their ball-bearings at the same time that the upper boxes move upon their ball-bearings, the result being that a compound or 30 gyratory motion will be imparted to the upper boxes and a horizontally-vibratory motion to the lower boxes. The material upon the screens of the upper boxes will therefore 35 be caused to move in a series of small ellipses, as hereinafter explained.

The shaft 21 is arranged to be operated from a system of counter-shafting 24 and a belt 25 and will be preferably provided with 40 a balance-wheel 26 to insure steadiness of action.

Each of the compartments of the upper boxes will be provided with an inlet-chute 27, through which the product from the reduction-mills will be conducted to the compartments. Each compartment will thus be independently supplied from a separate reduction-mill or with a separate product from the reduction-mills. Each of the intake-chutes 45 50 27 will be provided with a section of flexible tubing 28, so that the gyrations of the boxes will not be imparted to the inlet-chutes or hoppers.

Each compartment of each upper box will be provided with a series of separating-screens 55 60 65 29 with intermediate "gather-boards" 30, the screens and gather-boards so arranged that all the "tailings" from the screens of each compartment will be conducted to a discharge-spout 31, leading from each compartment in the upper box to its companion compartment in the lower box, while the material passing through all the screens will be run together and discharged by a spout 32 outside the apparatus. The screen 29 will be graduated to separate out the fine flour which will be discharged by the outlet 32, while the coarse

material consisting of farina, middlings, bran, shorts, &c., will be run together and discharged into the compartments in the lower 70 boxes by the spouts 31. By this means the fine flour contained in the material received from the reduction-mills is separated out from the mass in the upper boxes, leaving nothing but the coarser material to be treated in the 75 lower boxes. The separations in the upper boxes, as will be noted, are wholly by gravity, no induced air-currents being employed in the upper boxes. As before stated, the movement imparted to the upper boxes is a compound one, causing the material to move over the screens in small ellipses or circles, imparting to the particles a rolling motion which causes a very effectual separation of the finer 80 from the coarser particles, with the result 85 that the particles of the fine flour are thoroughly separated out from the coarser particles of the material and require no further treatment.

The different compartments of the lower 90 boxes 11 are each provided with a system of screens and chutes, whereby the material received from the upper boxes is separated into its component parts. The upper screen of each of these lower compartments is represented at 34 and receives all the material passing through its respective spout 31, the tailings from the screen 34 passing to a spout 35, by which it will be discharged. Beneath the screen 34 is a reversely-inclined grooved 95 plate 36, adapted to receive the product of the screen 34 by means of a gather-board 37, which is arranged to conduct the material passing through the screen 34 to the upper 100 end of the grooved plate 36. The function 105 of the grooved plate is to separate the valuable particles of farina from the coarser material by causing it to be rolled over and over, as hereinafter explained. Between the grooved 110 plate 36 and the gather-board 37 is a wind-trunk 38, having a series of apertures communicating with the space above the grooved plate and covered with a correspondingly-perforated damper-plate 39, adapted to be operated from outside the box, as by a rod 40. 115 By this means the force of the air-currents may be regulated, as hereinafter shown.

All the wind-trunks 38 of all of the compartments in each box 11 lead to a central trunk 41, communicating with a fan 42 by 120 conductor-trunks 43, as shown. The tailings from the grooved plate 36 pass to another screen 44, and the tailings from this screen are received by a chute 45 and discharged from the machine, while the material passing through the screen 44 is caused to pass to another screen 46 by a gather-board 47. The tailings from the screen 46 pass to a discharge-chute 48, while the material passing through the screen 46 is conducted by a gather-board 49 to another inclined grooved plate 50, similar to the grooved plate 36. Between the grooved plate 50 and the gather-board 49 is a wind-trunk 51, similar to the wind-trunk 38 and com-

municating, like the latter, with the main central trunk 41. In the bottom of the wind-trunk 51 are a series of apertures covered by a perforated damper-plate 52, adapted to be operated from outside the casing by a rod 53, the construction of this damper being similar to the damper 39 and its rod 40. The tailings from the grooved plate 50 are discharged by a spout 54. By this arrangement all the tailings from the several systems of screens in the boxes 11 are conducted by separate spouts from the boxes, while the material passing through the screens is caused to pass to the next screen below and to the grooved plates and be subjected to the influence of the induced air-currents while thus passing over the screens and plates.

The material passing through the screen 34 consists of farina, middlings, fine particles of bran, and fine light dust and other finer particles of refuse, and the action of the grooved plate 36 is to cause the material to roll over and over as it flows over the plate. This causes the material to be thoroughly separated, the finer particles of farina falling to the bottom of the mass and the coarser and lighter particles of material rising to the top, where the lighter particles are subjected to the influence of the air-currents and will be drawn off through the damper 39 into the wind-trunk 38, and thence out through the fan to the dust-collector, while the tailings in the separated condition pass to the next screens 44 and 46, where the coarser particles are again separated out and discharged from the spouts 45 48 and the final product of the final screen 46 passed to the grooved plate 50, where it is again caused to roll over and over, and be thereby placed in the best condition to be subjected to the action of the air-currents through the damper 52, which separates the remaining dust and finer particles, leaving nothing but the purified material to pass to the spout 54, while the "groats" and other coarse refuse pass to the discharge-spout 48. This is in general the operation, but may be varied as required, according to the condition and composition of the material to be treated.

By modifying the screens the apparatus may be adapted to separate the material into as many grades as required by increasing or decreasing the screens and adjusting them to suit the conditions of the material. I do not, therefore, wish to be limited to any specific arrangement or number or relative location of the screens and other parts of the apparatus employed in separating the material.

Some means will be required for keeping the screens clear from being clogged, and an improved arrangement of brushes for accomplishing this purpose is shown in Figs. 3, 5, 6, and 8.

The sieve-boxes 10, as before stated, being caused to gyrate in small ellipses or circles require a slightly different form of brush to clean the screens therein than the brushes

employed to clean the screens of the casings 11, which vibrate longitudinally only. In both boxes the brushes 55 are similar, being substantially spherical and provided with cavities 56 in their "heads," in which balls 57 loosely move, so that as the screens are rapidly vibrated the loose balls are caused to strike the sides of the cavities in the heads of the brushes and cause them to be thrown violently in the opposite direction, and thus greatly increase the brushing action.

The screens of the boxes 10 will be divided into compartments by diagonal guard-strips 80 58, elevated above the surface of the screen-cloth to form stops to the brushes, but which will allow the material to flow beneath them, each compartment having one of the spherical brushes therein, as shown in Fig. 3. By this means as the screens are rapidly vibrated the brushes will be violently rolled around over the screen-cloth and thoroughly clean it and prevent it from becoming clogged by the material flowing over it. The brushes 90 employed on the system of screens in the lower boxes will be preferably united by flexible coupling wires or cords 59, which serve to retain them horizontally disposed upon the screen-cloth, but at the same time allow them 95 sufficient movement to reach every part of the screen-cloth. By this improved apparatus the fine flour is separated out from the mass of the reduced material in the upper boxes by gravity only, thereby obviating any 100 tendency of loss of valuable particles by the action, and the remainder of the unseparated material separated into its component parts by the combined action of gravity and induced air-currents. By its peculiar arrangement and combination of parts an apparatus 105 of large capacity can be thus erected and operated within a small area and with the expenditure of a comparatively small amount of power. The apparatus is thus very economical both to build and to operate. Preferably the boxes 10 and 11 will be arranged in reverse transverse and longitudinal relations, as shown—that is to say, the boxes 10 all lying parallel and the boxes 11 all lying 110 parallel, but at right angles to the boxes 10, as this arrangement provides best for the reverse arrangement of the ball-bearing troughs; but I do not wish to be limited to this arrangement, as the boxes may all be arranged 115 in parallel relations. All the chutes leading to and from the boxes, as well as the wind-trunks from the fans, will be provided with the flexible fabric joints, as shown.

All the flexible joints in the conductor-chutes will be provided with wire supporting-frames to prevent them from collapsing.

Under certain circumstances it may be found necessary to extend the discharge-spouts 31 laterally, as shown at 31^a in Figs. 130 9 and 10, to increase the distance which the material will be caused to travel between the upper and lower series of compartments and also to enable the material to be fed into the

lower compartments at points other than shown in Figs. 1 and 2.

Having thus fully described my invention, what I claim as new, and desire to secure by 5 Letters Patent, is—

1. In an apparatus for the manufacture of flour, a primary and a secondary separating apparatus, runways for the latter having ball-bearings upon which it has a longitudinally-10 reciprocatory motion, runways interposed between the primary and the secondary apparatus whereby the former has a reciprocatory motion transverse to that of the latter, a vertically-disposed shaft, and a crank upon said 15 shaft connected with the primary separating apparatus, whereby the latter will receive a gyratory and the secondary separating apparatus a reciprocatory motion.
2. In an apparatus for the manufacture of 20 flour, a primary and a secondary separating apparatus, runways for the latter having ball-bearings upon which it has a longitudinal reciprocatory motion, runways interposed between the primary and the secondary apparatus, whereby the former has a reciprocatory motion transverse to that of the latter, means 25 for dividing the primary and secondary devices into corresponding compartments, connecting means between the compartments of the primary and the secondary apparatus, and operating means whereby the primary separating apparatus will receive a gyratory, and the secondary separating apparatus a reciprocatory motion.
3. An apparatus for the manufacture of 30 flour, comprising an upper and a lower sieve-box having corresponding compartments flex-

ibly connected, inlets to the compartments of the upper sieve-box, supporting means for the lower sieve-box whereby it may have a 40 reciprocatory movement, supporting means upon the said lower sieve-box for the upper sieve-box, said supporting means comprising runways and interposed antifriction - balls whereby the said upper sieve-box may have a 45 reciprocatory motion transversely to that of the lower sieve-box, a vertically-disposed drive-shaft, a counter-shaft extending through a cavity in the lower sieve-box and having a crank connection with the upper sieve-box, 50 means for transmitting motion from said drive-shaft to the counter-shaft, whereby a gyratory motion will be imparted to said upper sieve-box and a reciprocatory motion to the lower sieve-box, and independent discharging means for the products of the screens 55 within said sieve-boxes.

4. In an apparatus for the manufacture of flour, a separator having a series of screens, means for imparting a compound transverse 60 and lateral movement to said screens, diagonal dividing-ribs above said screens dividing the space above them into angular-sided compartments, brushes operating loosely in said compartments and having irregular cavities 65 in their heads, and balls loosely disposed in said cavities, substantially as set forth.

In testimony that I claim the foregoing as my own I have hereto affixed my signature in the presence of two witnesses.

LUDVIG KORÁB.
